US00D831896S

(12) **United States Design Patent** (10) **Patent No.:** **US D831,896 S**
(45) **Date of Patent:** **** Oct. 23, 2018**

(54) **FINGER MITT**

(71) Applicant: **Meah Krahe**, Chicago, IL (US)

(72) Inventor: **Meah Krahe**, Chicago, IL (US)

(**) Term: **15 Years**

(21) Appl. No.: **29/605,974**

(22) Filed: **May 31, 2017**

(51) **LOC (11) Cl.** **02-06**

(52) **U.S. Cl.**

USPC **D29/114**

(58) **Field of Classification Search**

USPC D29/100, 113, 114, 115, 116.2; D2/617

CPC A41D 13/087; A41D 19/01

See application file for complete search history.
